(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is another front view thereof, showing the design with different broken line subject matter.

The broken lines shown connecting the circular icons and surrounding the lower central circle are included in the claimed design.

The remaining broken lines illustrate a display screen or portion thereof and elements of a graphical user interface, including all text, that form no part of the claimed design.
